PREFABRICATED BUILDING UNIT FOR AUDIO AND/OR VISUAL EQUIPMENT

Tadashi Hanaoka, Kawasaki, Isao Kaneko, Tokyo, and
Iwao Shiina, Yamato, Japan, assignors to Misawa
Homes Co., Ltd., Tokyo, Japan

Filed Nov. 6, 1972, Ser. No. 303,810

Claims priority, application Japan Sept. 19, 1972

Term of patent 14 years

Int. Cl. D25—02

U.S. Cl. D13—1 R

FIG. 1

FIG. 3

FIG. 2

FIG. 4

FIG. 5

FIG. 6

FIG. 7

FIG. 8

FIG. 9

FIG. 1 is a top plan view of a prefabricated building unit for audio and/or visual equipment showing our new design;

FIG. 2 is a front elevational view thereof;

FIG. 3 is a right side elevational view thereof;

FIG. 4 is a bottom plan view thereof;

FIG. 5 is a rear elevational view thereof;

FIG. 6 is a cross sectional view on line VI—VI of FIG. 2;

FIG. 7 is a perspective view thereof;

FIG. 8 is a front elevational view of the subject building unit in an operative state; and

FIG. 9 is a cross sectional view of the subject building unit in an operative state.

The elements shown in dashed lines in the figures are for illustrative purposes only.

We claim:

The ornamental design for a prefabricated building unit for audio and/or visual equipment, as shown and described.
